(57) **CLAIM**

The ornamental design for a charging case for earphones, as shown and described.

DESCRIPTION

FIG. 1 is a front elevational view of our new design for a charging case for earphones;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top, right side perspective view thereof; and,

FIG. 8 is a rear, right side perspective view thereof.

The broken lines consisting of evenly spaced dash lines in the drawings depict portions of the charging case for earphones that form no part of the claimed design.

The broken lines consisting of short and long dash lines encircle areas that form no part of the claimed design.

1 Claim, 8 Drawing Sheets
